MICHAEL J. MILMOE, OF CHICAGO, ILLINOIS, ASSIGNOR TO F. B. REDINGTON COMPANY, OF CHICAGO, ILLINOIS, A CORPORATION OF ILLINOIS

WRAPPING AND SEALING MACHINE

Application filed October 28, 1926, Serial No. 144,725. Renewed December 12, 1930.

This invention relates to a machine for wrapping and sealing articles in a package, and has for one of its objects the provision of such a machine which will enclose the articles wrapped in an air-tight package.

A further object is to provide a machine of the class described which shall be of improved construction and operation.

Other objects will appear from the following description.

The invention is exemplified in the combination and arrangement of parts shown in the accompanying drawings and described in the following specification, and it is more particularly pointed out in the appended claims.

In the drawings—

Fig. 1 is an elevation of a machine embodying the present invention;

Fig. 2 is an elevation looking from the left in Fig. 1;

Fig. 3 is a fragmentary elevation of a portion of the positioning mechanism for the articles to be wrapped;

Fig. 4 is a view looking from the right in Fig. 3;

Fig. 5 is a section substantially on line 5—5 of Fig. 4;

Fig. 6 is a section on line 6—6 of Fig. 10;

Fig. 7 is a fragmentary elevation of the machine showing the wrapping mechanism on a larger scale than illustrated in Fig. 2;

Fig. 8 is a somewhat diagrammatic view of the driving gearing for parts of the machine;

Fig. 9 is a top plan view of the transfer mechanism for the articles to be wrapped;

Fig. 10 is an elevation of the sealing mechanism;

Fig. 11 is a plan view of one of the sealing jaws;

Fig. 12 is an elevation of a part of the folding mechanism;

Fig. 13 is a somewhat diagrammatic view showing the end folding mechanism;

Fig. 14 is an elevation of the mechanism shown in Fig. 12, but with the parts in a different position;

Fig. 15 is a section substantially on line 15—15 of Fig. 14;

Fig. 16 is a top plan view of the transfer mechanism showing the end crimping plates in operation;

Fig. 17 is a fragmentary plan of a portion of the end folding guideway;

Fig. 18 is an elevation of the end folding guideway, with parts in section on line 18—18 of Fig. 17;

Fig. 19 is a section substantially on line 19—19 of Fig. 11;

Fig. 20 is a section on line 20—20 of Fig. 19;

Fig. 21 is a diagrammatic plan showing the operation of the end crimping plates;

Fig. 22 is an end view of the article and wrapper after the ends of the wrapper have been crimped;

Fig. 23 is a plan view of the package after the wrapper has been crimped and sealed;

Fig. 24 is a section on line 24—24 of Fig. 23.

In wrapping many articles it is desirable to seal the articles in a package which is air-tight in order to properly preserve the wrapped article. Waxed or paraffine paper is commonly used for providing an air-tight wrapping but in order to make the wrapping really tight it is necessary that there shall be no unsealed folds affording passage to the interior of the wrapper.

In the present invention the wrapper is folded about the article with the edges overlapping on three sides of the article and extending face to face and the overlapping edges are then sealed together by the application of heat which partially melts the paraffine and the melted paraffine is then chilled to completely seal the contacting faces of the wrapper. The wrapper thus sealed is illustrated in Figs. 23 and 24 of the drawings. The projecting edges are then folded against the portion of the package containing the wrapped article. By sealing the edges of the wrapper while they project away from the article it is possible to effect the sealing without subjecting the article to the heat of the sealing irons. It is also possible to insure uniform pressure against the portions of the wrapper to be sealed which cannot be done where it is attempted to seal the flaps against the sides of the wrapped article. By way of

illustration a machine is shown in the draw-

ings for wrapping candy chewing gum briquettes, but it will be understood that the invention is not confined to a machine for wrapping particular articles, but may be applied to wrapping a large variety of commodities.

In the drawings, the numeral 30 designates the base or supporting frame for a wrapping machine having a driving pulley 31 which may be driven from any suitable source of power. The pulley 31 is connected by a belt 32 to a pulley 33 on a shaft 34 and the gearing 35 connects the shaft 34 with the main drive shaft 36. The drive shaft 36 may be provided with a handle 37 by means of which the machine can be operated by hand for inspection or other purposes, when desired.

At the top of the frame 30 is a hopper 38 in which the briquettes to be wrapped are placed. Suitable feed rollers and agitating mechanism are provided at the base of the hopper 38 driven by a belt 39 extending upwardly from the shaft 34. The briquettes are directed from the hopper 38 into downwardly extending guideways 40 and 41 in which the edges of the briquettes travel in grooves in guide bars 42, 43 and 44, as illustrated more clearly in Fig. 3. Positioned below the lower ends of the guideways 40 and 41 is an assembling wheel 45 having disc portions 46 and 47 differing in diameter so that the disc 46 projects radially beyond the disc 47 by an amount equal to the length of one of the briquettes which are shown at 48 in Fig. 3. The discs 46 and 47 are provided with radial grooves 49 and 50, respectively, into which the briquettes enter from the lower ends of the guideways 40 and 41. The grooves 49 and 50 extend inwardly to the same radial distance from the axis of the wheel 45, the depth of the groove in the disc 47 being equal to the length of one briquette, while the depth of the groove in the disc 46 is equal to the length of two briquettes. A circular groove 51 extends inwardly from the outer lateral face of the disc 46 and a bracket 52 is mounted on the supporting frame 30 and provided with an arcuate flange 53 which extends into the groove 51 and has its outer face flush with the outer periphery of the disc 47. It will be apparent that the briquettes entering the groove 49 in the disc 46 will be arrested by the flange 53 so that a single briquette will be admitted at one time and will be held by the flange 53 with its inner end in registration with the outer end of the briquette in the groove 50 of the disc 47.

The wheel 45 is intermittently rotated by 90° steps and between successive rotations is brought to rest with the radial grooves in registration with the guides 40 and 41. Each time the wheel comes to rest a pair of briquettes are deposited in the grooves registering with the guides 40 and 41 and at the next rotation the briquettes are brought to a position on a level with the axis of the assembling

wheel and are arranged flat side down, as shown at the left in Fig. 4. The wheel 45 may be rotated by any suitable driving mechanism, such as a lever 54 engaging a ratchet wheel 55 on the shaft 56 which supports the wheel 45. The lever 54 is oscillated by a rod 57 operated by a cam 58 on the main drive shaft 36. The mechanism may be timed to impart a quarter of a rotation to the wheel 45 for each revolution of the drive shaft 36.

A receiving platform 59 is mounted on the frame 30 and has its upper surface disposed in registration with the lower faces of the briquettes 48 held in the slots 49 and 50 extending horizontally in the wheel 45. The relative position of the receiving platform and the briquettes in the assembling wheel is shown in Fig. 5. The briquettes are transferred from the wheel 45 to the receiving platform 59 by a transfer finger 60 mounted on the upper end of a lever arm 61, the lever arm 61 being pivoted at 62, as shown in Fig. 2, and oscillated about its pivot by a link 63 secured to an arm 64 which is pivoted at 65 on the frame 30 and provided with a cam roller 66 which engages a cam groove in a cam wheel 67 secured to the main drive shaft 36. The arm 61 is timed to oscillate during the pause in the rotation of the wheel 45 and the movement of the finger 60 brings the two briquettes into alignment with each other and transfers them from the wheel 45 to the platform 59. A guide plate 68 is spaced above the platform 59 and carries guide members 69 into which paper wrappers 70 are fed in a vertical position by any suitable paper feed mechanism, not shown. The briquettes 48 are moved forwardly on the platform 59 by the finger 60 until they pass the transverse opening for the wrappers 70, as illustrated in Fig. 7. This will fold the upper and lower edges of the wrapper 70 backwardly against the top and bottom faces of the briquettes and draw the folded flaps into the opening between the platform 59 and upper guide 68. When the finger 60 is returned the briquette will be deposited in the opening between the platform and guide with the upper and lower flaps of the wrapper folded backwardly on the top and bottom faces of the briquettes.

The platform 59 is provided with slots 71 and 72 over which the briquettes 48 are moved by the finger 60. An arm 73 is pivoted at 74 on a horizontally extending arm 75 which in turn is pivotally mounted at 76 on the frame 30 and oscillated vertically by a cam 77 on the shaft 36. The arm 73 is connected by a link 78 on the arm 64 so that both vertical and horizontal movement is imparted to the arm 73. The arm 73 carries a pair of fingers 79 and 80 which are pivoted at 81 on the end of the arm 73 and are spaced apart to register with the slots 71 and 72 in the platform 59. The fingers 79 and 80 are resiliently held by springs 83 which tend to rotate

the top ends of the fingers forwardly or to the right, as viewed in Fig. 7. The movement of the arm 73 projects the fingers 80 upwardly through the slots 71 and 72 in the rear of the briquettes after the finger 60 has been withdrawn, leaving the briquettes in the foremost position to which they are moved by the finger 60. Each of the fingers 79 and 80 is provided with a forwardly projecting nose piece 84 which enters between the backwardly directed flaps of the wrapper and engages the rear edge of the briquette. The fingers are then moved forwardly and discharge the briquettes from the forward edge of the platform 59.

The briquettes are received in pockets in a turret 85 which is mounted on a shaft 86' projecting from the frame 30. As the briquettes are discharged into the pockets of the turret 85 the parts of the wrapper folded about the forward edges of the briquettes are crimped at their ends by crimping plates 86, one at each side of the turret 85. The crimping plates 86 are carried on lever arms 87 which are pivoted on a stud shaft 88 projecting outwardly from the machine frame. Each lever 87 carries an arm 89 attached to a spring 90 tending to rotate the lever in a clockwise direction, as viewed in Fig. 7. The lower ends of the lever arms 87 are positioned in the path of abutment blocks 91 on the arm 73 so that as the arm 73 moves to the right in Fig. 7 it strikes the lower ends of the levers 87 and moves the crimping plates 86 rearwardly to engage the folded edge of the wrapper 70 and press the folded portion backwardly between the end flaps, as indicated in Figs. 16 and 21. The rear contact edges of the crimping plates 86 are beveled, as indicated at 92, to facilitate the crimping action of the plates on the wrapper.

After the briquettes are positioned in the pocket of the turret 85 and the fingers 80 and crimping plates 86 have been withdrawn, the briquettes will be carried upwardly in the direction of the arrow in Fig. 7 by rotation of the turret. It will be noted that the platform 59 projects beyond the upper guide member so that the briquettes need not be discharged entirely from the supporting platform to permit them to be lifted by rotation of the turret. The pockets in the turret are formed by fixed contact members 93 and spring-held clamps 94. The clamps 94 are shorter than the members 93 and the members 93 may be provided with recesses 95, as shown in Fig. 9, to pass the projecting end of the central supporting portion 96 of the supporting platform 59. When the briquettes are clamped by the jaws 93 and 94, rotation of the turret wheel will lift the briquettes from the support 59.

The shaft 86' which carries the turret wheel 85 is driven by a Geneva drive comprising an arm 97 mounted on a shaft 98 and having a

collar 99 for holding the driven member stationary in its various stations. The driven member 100 is secured to the shaft 86' and is provided with slots 101 for receiving a roller 102 on the arm 97 and with arcuate recesses 103 for engaging the collar 99. The collar 99 is provided with a cut-away portion 104 to permit the bifurcations forming the recesses 103 to pass the collar during rotation of the driven member by the roller 102. The shaft 98 is driven by a sprocket wheel 105 operated by a sprocket chain 106 which passes over a driving sprocket 107 on the main drive shaft 36. The sprockets 107 and 105 are of the same size so that the turret 85 is rotated one step for each rotation of the main drive shaft 36. This brings a new pocket into registration with the supporting platform 59 for each pair of briquettes discharged from the platform. After the briquettes are lifted from the supporting platform 59 and transferred to the first station by the turret 85, the turret remains stationary while the edges of the wrapper are sealed by a sealing clamp located adjacent the first station stop of the turret above the platform 59. This sealing clamp comprises a pair of jaws 108 and 109 shown in open position in Fig. 7 and in closed position in Fig. 10. The jaw 109 is secured to a collar 110 by a screw 111, as shown more clearly in Fig. 20. The collar 110 is clamped to a shaft 112 by a cap screw 113. The jaw 108 is provided with lugs 114 at opposite sides of the collar 110 which are journaled on the shaft 112. A gear segment 115 is also journaled on the shaft 112 and is connected with the jaw 108 by means of an arm 116 and a spring 117. The shaft 112 is journaled in the frame 30, as shown in Fig. 6, and is provided with a gear segment 118 at one side of the frame member 30 and a gear segment 119 at the opposite side. The arm 116 is connected to the gear segment 119 by screws 120. A stud 121 is threaded into the collar 110 and is surrounded by a spring 122 which engages a plate 123 connected with the jaw 109 which permits yielding movement of the jaw relative to the collar 110. It is thus apparent that the jaw 109 is yieldingly connected to the shaft 112 and that the jaw 108 is yieldingly connected to the gear segment 115 journaled on the shaft 112.

A second shaft 124 is journaled in the frame member 30 in spaced relation to the shaft 112 and is provided with a gear segment 125 meshing with the gear segment 118. A gear segment 126 is journaled on the shaft 124 at the forward side of the frame member 30 and is connected by a spring 127 with a clamping jaw 128 journaled on the shaft 124 and similar to the jaw 108. A second clamping jaw 129 is secured to a collar 130 fixed to the shaft 124 in a manner similar to the collar 110 on the shaft 112. The jaws 128 and 129 are shown in open position in Fig. 7 and in closed

position in Fig. 10. An idler segment 131 is journaled on a stud shaft 132 mounted on the frame 30. The idler segment 131 has a sufficiently wide face to mesh with the gear segments 119 and 126 and the segment 126 also meshes with the segment 115. An operating rod 133 is pivoted to the segment 118 at 134 and is reciprocated lengthwise by means of a rocker arm 135 operated by a cam 136 on the main drive shaft 36. The operating rod 133 is provided with a spring 137 which permits yielding downward pressure to be exerted on the rod. When the rod 133 is raised from the position shown in Fig. 10 to the position shown in Fig. 7, the shaft 112 will be rotated in a counter-clockwise direction and the shaft 124 will be rotated in a clockwise direction, as viewed in these figures. The jaw 109 will move in unison with the shaft 112 and the jaw 129 will move in unison with the shaft 124. The movement of the jaw 129 will be more rapid than that of the jaw 109 because of the inequality of the radii of the gear segments 118 and 125. This will move the jaw 129 out of the way of the jaw 109 so that they will not interfere with each other. During the upward movement of the rod 133 the gear segment 119 will move the shaft 112 and will rotate the segment 131 in a clockwise direction. Since the segment 131 meshes with the segment 126 the segment 126 will move in a counter-clockwise direction to throw the jaw 128 upwardly to the open position shown in Fig. 7. The segment 126 meshes with the segment 115 so that this segment will move clockwise to throw the jaw 108 outwardly into the position shown in Fig. 7. In other words, both sets of jaws are open during the upward movement of the rod 133 and by reverse action are closed during the downward movement of the jaws. The cam for operating the rod 133 is shaped to close and open the jaws during the pause of the turret, the jaws remaining open during the movement of the turret.

Each of the jaws 108, 109, 128 and 129 is provided with a recess 138 shown best in Figs. 19 and 20 for receiving the briquettes 48. Surrounding the recesses 138 are gripping members 139 which clamp the projecting edges of the wrapper 70 and squeeze the edges together about the briquettes, as shown in these figures. The clamping members 139 of the jaws 108 and 109 are provided with heating elements 140 which are in the form of electrical resistance wires supplied with current from leads 141 which extend through the shaft 112.

The projecting edges of the wrapper are squeezed together and at the same time the wax or other material with which the wrapper is treated is softened by the heat of the elements 140 so that the edges of the wrapper are sealed together, completely closing the wrap- 65 per and forming an air-tight package. The

contact members 139 of the jaws 128 and 129 are not heated but act as chilling devices by means of which the melted wax is again hardened so that the flaps will not be separated by further manipulation. The jaws 128 and 129 are preferably provided with radiation fins 142 for dispersing the heat from the jaws and keeping them cool. In this way the projecting edges of the wrapper are first heat-sealed together and thereafter chilled to insure that the sealed parts will remain together. 75

After the wrapper has been sealed and chilled, the package is carried by the next movement of the turret to the fourth station. During this movement it passes a wiper 143 which is pivoted to swing on a stud shaft 144 projecting from the frame 30 so that the depending wiper will engage the projecting flap of the package to bend the flap backward against the side of the package, as shown in Figs. 7 and 12. The wiper 143 is provided with projecting fingers 145 at each end thereof to engage the portion of the wrapper projecting beyond the ends of the wrapped articles. Secured to a shaft 146 adjacent the station at which the package is brought to rest is a creaser 147 having creasing flanges 148 at each end thereof for pressing the folded portion of the wrapper against the ends of the wrapped article. The flanges 148, as shown in Fig. 15, are spaced apart an amount corresponding to the length of the package so that when the creaser is moved against the side of the package the flanges will extend adjacent the ends of the package and press the folded flap to a position against the end flaps. The end flaps are later folded over the ends of the package and the creasing process is for the purpose of preventing the folded edge flap from bulging backwardly when the end flaps are folded over. The wiper holds the edge flap in folded position, as shown in Fig. 12, while the creaser 147 rotates in a counter-clockwise direction causing the creasing flanges 148 to approach and contact with the folded flap. At the time that the edges of the flanges 148 reach the center line of the package the turret begins its forward movement and the turret and creaser travel together to carry the package between the end folders 149. The position of the package between the end folders 149 is shown more clearly in Fig. 13 and the creases formed by the creasing flanges 148 are indicated at 150. 115

The final movement of the package by the turret carries the package to a position diametrically opposite the first position. In this final position the package is brought into alignment with an opening 151 between upper and lower guides 152 and 153, respectively. A pair of discharge fingers 154, one at each side of the turret, discharge the package from the turret into the opening 151. The upper guide 152 is provided with tapered recesses 155, one at each side of the guide, for receiv- 130

ing the backwardly bent end flaps of the package. These recesses are tapered, as shown in Figs. 17 and 18, to fold the end flaps inwardly against the side of the package as the package is moved forwardly in the opening 151 by the fingers 154. The fingers 154 are supported on arms 156 pivotally mounted on the shaft 65 and oscillated by a cam on the main drive shaft 36. The fingers 154 carry the package entirely through the opening 151 and discharge it into grippers 157 on a turret 158 secured to a shaft 159. The shaft 159 is rotated in unison with the shaft 86 by means of a gear 160 on the shaft 86 and an idler 161 on a stud shaft 162. The shaft 146 is rotated by a chain of gears 163, Fig. 1, which are driven by a gear on the shaft 164 which carries the uppermost sprocket 165 driven by the chain 106. An outer wrapper 166 is interposed in a guide 167 extending transversely of the passage 151 and this outer wrapper is folded about the forward edge of the package as it passes through the opening 151. The wrapper extends sufficiently above the opening 151 so that the top flap of the wrapper will extend outwardly away from the package, as shown in Fig. 7. The rear face of the projecting flap is treated with a small amount of adhesive material by a swinging arm 168 or other suitable pasting mechanism. The wrapper is discharged from the turret 158 by a pair of fingers 169 into a passage 170 having a spring guide 171 at the top thereof. The guide 171 is provided with a folder plate 172 which folds the projecting flap backwardly against the edge of the passage and glues the flap in place, thus placing an outer wrapper about the sealed package. A magazine is provided at the end of the passage 170 and a rotary cam disc 174 is disposed below the open lower end of the magazine and raises the packages into the magazine as they reach the end of the passage 170. The cam disc 174 is secured to a shaft 175 connected by spur gears to a shaft 176 which is provided with a sprocket 177 driven by the sprocket chain 106. The fingers 169 are carried on arms 178 which are connected by links 179 to the arms 156 so that the arms 178 and the arms 156 are oscillated in unison with each other.

The operation of the various parts has been explained in connection with the description of the parts so that a detailed description of the operation of the machine is thought to be unnecessary. Briquettes are deposited in the hopper 34 and are automatically wrapped in treated wrappers which are sealed by pressing together the projecting edges of a wrapper, after which the edges are folded against the package and a band or outer wrapper is placed in position to hold the folded edges in place. The briquettes are assembled in packages of two briquettes each, although it will be understood, of course, that

the invention is not limited to the number of articles placed in a single package.

I claim:

1. In a wrapping machine, a pair of guideways disposed side by side, means for supplying articles to said guideways, a rotary member having pockets therein movable into and out of alignment with said guideways to receive articles from said guideways, means for discharging the articles from said pockets in alignment with each other, and means for placing a wrapper about the aligned articles. 70

2. In a wrapping machine, a pair of guideways arranged side by side, means for supplying articles to said guideways, means for extracting one article from each of said guideways, and means for alining the articles extracted with different sides thereof adjacent each other from the sides which were adjacent when the articles were in the guideways. 85

3. In a wrapping machine, a pair of guideways disposed side by side, means for supplying articles to said guideways, a receiver having pockets therein spaced from one another in the direction of the line of articles in said guideways and arranged to receive one article at a time from said guideways respectively, and means for moving the article received from one guideway transversely of the direction of the line of articles in the guideways to bring said article into alignment with the article received from the other guideway. 100

4. In a wrapping machine, a pair of guideways arranged side by side, means for supplying a series of articles to each of said guideways, means for receiving one article from each of said guideways respectively at points displaced from one another in the direction of the length of said guideways by an amount equal to the length of one of said articles, and means for shifting one of said articles transversely of the direction of the length of said guideways to bring said article into alignment with the article received from the other guideway. 110

5. In a wrapping machine, a pair of upright guideways arranged side by side, means for extracting an article from the lower end of each of said guideways at points spaced from one another in the direction of the length of said guideways by an amount equal to the length of one of said articles, means for transferring the articles extracted from said guideways from a vertical to a horizontal position, and means for shifting one of said articles transversely relative to the other to bring said articles into alignment. 115

6. In a wrapping machine, a pair of upright guideways disposed side by side, means for supplying articles to each of said guideways, a rotary member disposed adjacent the lower ends of said guideways, the lower end 130

of one of said guideways being spaced below the lower end of the other of said guideways, means for rotating said rotary member to shift the articles received thereby away from the series of articles in the guideways, and means for shifting one of said articles into registration with the other.

7. In a wrapping machine, a rotary member having receiving pockets therein offset from one another in the direction of the axis of said rotary member and spaced outwardly from the axis of said member different distances, means for supplying articles to said pockets, and means for shifting one of said articles in the direction of the axis of said rotary member to bring said article into alinement with the other.

8. In a wrapping machine, a pair of guideways disposed side by side, a rotary member having portions thereof spaced from one another in the direction of the axis of said member and in alinement respectively with said guideways, the portion of said rotary member alining with one of said guideways having a longer radius than the portion alining with the other of said guideways, said portions having pockets therein for receiving articles from said guideways respectively, means for rotating said member to transfer the articles received thereby away from the articles remaining in said guideways, and means for shifting the article received by one of said portions in the direction of the axis of said rotary member into alinement with the article received by the other portion.

9. In a wrapping machine, a pair of guideways arranged side by side, means for supplying articles in a series in each of said guideways, the end of one of said guideways being disposed below and at one side of the other of said guideways, a receiving wheel having radial pockets therein movable into alinement with said guideways respectively, and a support for holding the articles deposited in one of said pockets spaced radially a greater distance from the axis of said wheel than the articles disposed in the other of said pockets.

10. In a wrapping machine, a pair of guideways disposed side by side, a receiving wheel having portions thereof of different diameters registering with said guideways respectively, radially extending pockets in said portions extending inwardly to substantially the same distance from the axis of said wheel, means for holding the articles received in a pocket in the portion having the greater diameter at a greater distance from the axis of said guideway than articles received in a pocket in the other portion, and means for shifting one of said articles in the direction of the axis of said wheel to bring said articles into alinement.

11. In a wrapping machine, an assembling wheel having a radial pocket therein, means

for supplying an article to said pocket, means for preventing the article supplied to said pocket from moving inwardly toward the axis of said wheel to the bottom of said pocket, and means for moving a second article transversely of said pocket into alinement with said first named article in said pocket.

12. In a wrapping machine, a pair of guides arranged side by side, a receiving wheel having radially extending pockets therein for receiving articles from said guides, means for holding the articles in said pockets at different radial distances from the axis of said wheel, and means for shifting an article from one of said pockets transversely thereof into alinement with the article in the other of said pockets.

13. In a wrapping machine, a pair of guideways disposed side by side, a receiving wheel having radial pockets therein for receiving articles from said guideways, means for retaining the articles in said pockets at different radial distances from the axis of said wheel during the rotation of said wheel, and means for alining the articles in said pockets and for discharging the alined articles from said pockets.

14. In a wrapping machine, a pair of upright guideways arranged side by side, a receiving wheel having radial pockets therein spaced from one another in the direction of the axis of said wheel to aline with said guideways, said pockets being arranged in pairs in said wheels, the pockets of each wheel registering with each other, means for holding articles in the pockets of each pair at different radial distances from the axis of said wheel, and means movable through the registering pockets in the direction of the axis of said wheel for discharging articles from said pockets and for alining the discharged articles.

15. In a wrapping machine, a pair of upright guideways arranged side by side, a receiving wheel having radial pockets therein for receiving an article from each of said guideways at one time, a support forming a horizontal guideway, means for transferring articles received from said upright guideways by said receiving wheel to said horizontal guideway and for alining said articles, and means for placing a single wrapper about the alined articles.

16. In a wrapping machine, a support forming a guideway, means for moving an article along said guideway, means supporting a wrapper across said guideway for folding it about the forward portion of said article as it moves along said guideway, and a crimper disposed adjacent the path of said article in position to engage the projecting portion of said wrapper to crimp the folded portion of said wrapper between projecting flaps thereof.

17. In a wrapping machine, a support

forming a guideway for articles to be wrapped, means for moving said articles along said guideway, means for folding a wrapper about the forward portion of said articles as they are moved along said guideway, a crimper disposed adjacent the path of the articles, and means for moving said crimper in a direction reverse to the direction of movement of said articles to crimp portions of the wrappers projecting from the articles.

18. In a wrapping machine, a support forming a guideway, means for moving articles along said guideway, means supporting wrappers across said guideway for folding wrappers about the forward portions of articles moved along said guideway, a turret for receiving articles from said guideway, means for rotating said turret to transfer the article received away from the guideway, and means for crimping portions of the wrappers projecting from the articles between projecting flaps of said wrappers.

19. In a wrapping machine, means for folding a wrapper about one side of an article to be wrapped to cause the edges of the wrapper to project from other sides of said article, means for crimping a portion of the wrapper at the folded side thereof between the projecting portions of said wrapper, and means for sealing the inner faces of the projecting portions of the wrapper together.

20. In a wrapping machine, means for positioning a pair of articles side by side, means for folding a wrapper about alining faces of said articles to cause the edges of said wrapper to project from other faces of said articles, means for crimping the folded portion of said wrapper between the projecting edges of said wrapper, and means for sealing the inner faces of the projecting edges of said wrapper together with the crimped portion therebetween.

21. In a wrapping machine, means for folding a wrapper about one face of an article to bring the edges of said wrapper into position to project from other faces of said article, jaw members for pressing the projecting edges of said wrapper together with their inner faces in contact with each other, and means for heating said jaw members to seal the projecting edges of the wrapper together.

22. In a wrapping machine, means for folding a wrapper about one face of an article, a turret having pockets therein, means for positioning the article with the wrapper thereon in one of said pockets with the wrapper folded about the innermost portion of the article while the edges of said wrapper project beyond the exposed portions of said article, and means for pressing the edges of said wrapper together while they project from the article to seal said edges together.

23. In a wrapping machine, a holding

member having a pocket therein, means for folding a wrapper about one side of an article, means for inserting the article and wrapper in the pocket with the folded portion of the wrapper about the inner side of the article and with the edges of the wrapper extending beyond the outer faces of the article, and means for sealing the inner surfaces of the projecting edges of the wrapper together.

24. In a wrapping machine, a holder having a pocket therein, means for folding a wrapper about one face of material to be wrapped, means for positioning the material with the wrapper thereon in said pocket with the edges of the wrapper projecting beyond said holder and the exposed portions of said material, and means for sealing the inner faces of the projecting edges of the wrapper together about the exposed portion of the material.

25. In a wrapping machine, means for supporting an article to be wrapped, and a pair of jaws having recesses therein forming a pocket to receive the article and having clamping members adjacent said recesses for gripping projecting flaps of a wrapper disposed about said article.

26. In a wrapping machine, means for supporting an article to be wrapped, a pair of jaws having recesses in engaging faces thereof to form a pocket when said jaws are closed for receiving said article, said jaws having clamping faces disposed adjacent said recesses for clamping projecting portions of a wrapper disposed about said article, and means for heating said jaws to seal the clamped portions of the wrapper.

27. In a wrapping machine, means for supporting an article to be wrapped, a pair of jaws having portions thereon for gripping projecting flaps of a wrapper disposed about said article, means for moving said jaws to grip said flaps, and means for heating said jaws to seal the gripped flaps together.

28. In a wrapping machine, a support for holding an article to be wrapped, a pair of jaws having means thereon for gripping and sealing wrapper flaps projecting from said article, means for opening and closing said jaws, and means for moving said support while said jaws are open, said support being stationary when said jaws are closed.

29. In a wrapping machine, a pair of jaws, means for closing said jaws against projecting portions of a wrapper disposed about an article, means for heating said jaws to seal said portions together, a second pair of jaws, and means for closing said second pair of jaws on the sealed portion of said wrapper subsequent to the sealing thereof.

30. In a wrapping machine, two pairs of jaws, means for closing one of said pairs of jaws against projecting portions of a wrapper disposed about an article to seal said

130

wrapper, means for moving said article from said first-mentioned pair of jaws into position to be engaged by the other pair of jaws, and means for closing said last-named pair of 5 jaws upon the projecting portions of the wrapper to chill the said portions.

31. In a wrapping machine, means for heat-sealing a wrapper, and a pair of chilling jaws for gripping the sealed portion of the 10 wrapper, said chilling jaws having fins thereon for radiating heat from said jaws.

32. In a wrapping machine, a turret having spaced pockets therein for holding articles to be wrapped, means for inserting articles 15 and wrappers in said pockets with the edges of said wrappers projecting beyond the articles, means for intermittently rotating said turret to bring each article thereon to successive stations about said turret, a pair of jaws 20 disposed at one of said stations, means for heating said jaws, means for closing said jaws upon the projecting portion of the wrapper, a second pair of jaws disposed at a subsequent station, means for closing said 25 jaws upon the projecting portion of the wrapper, and means for cooling said jaws.

33. In a wrapping machine, two pairs of jaws disposed to swing about parallel axes, gearing for opening and closing said jaws, 30 and means for transferring an article from one pair of said jaws to the other to permit said jaws to operate successively on said article.

34. In a wrapping machine, two pairs of 35 jaws arranged in spaced relation to each other, means for successively presenting an article to said jaws, means for opening and closing said jaws to cause said jaws to grip projecting edges of a wrapper on said article, 40 means for heating the jaws to which said article is first presented, and means for cooling the jaws to which said article is subsequently presented.

35. In a wrapping machine, two pairs of 45 jaws mounted to swing about parallel spaced axes, and means for simultaneously opening and closing said pairs of jaws, the adjacent jaws of said pairs being arranged to move at different speeds to prevent interference 50 thereof.

36. In a wrapping machine, two pairs of jaws arranged to swing about parallel axes, means for simultaneously opening and closing said jaws, a turret having spaced pockets 55 thereon for supporting articles to be presented to said jaws, and means for rotating said turret while said jaws are open to transfer the articles from one pair of said jaws to the other.

37. In a wrapping machine, a pair of spindles disposed side by side in parallel relation, a pair of jaws mounted on each of said spindles, means for shifting one of said jaws to open and close said jaw, gearing for operating the other jaw of the same pair simulta-

neously with said first-mentioned jaw but in an opposite direction to open and close said jaws, and gearing connecting each of said jaws with the corresponding jaw of the other pair of jaws to cause the jaws of each pair 70 to operate simultaneously.

38. In a wrapping machine, means for supporting on article having a wrapper thereon with the edges of the wrapper projecting beyond the article, a pair of jaws for gripping the projecting portion of the wrapper, means for heating said jaws, and resilient means for pressing said jaws together against said wrapper.

39. In a wrapping machine, a support for 80 an article to be wrapped, means for heat-sealing a projecting portion of a wrapper disposed about said article, a pair of jaws for engaging the sealed portion of the wrapper, means for cooling said jaws, and yielding 85 means for pressing said cooling jaws against said projecting portion.

40. In a wrapping machine, means for 90 folding a wrapper about an article with the edges of the wrapper projecting beyond the article, means for heat-sealing together the projecting edges of the wrapper at opposite sides of the article, means for creasing said projecting edges along lines adjacent the edges of the article, and means for folding 95 the projecting edges along the creased lines against the article.

41. In a wrapping machine, means for 100 folding a wrapper about an article so that the edges of said wrapper project from three 105 sides of the article, means for heat-sealing the projecting edges, means for folding the projecting edges of the wrapper at one side of the article backwardly against the article, means for creasing the backwardly folded 110 edges adjacent the edges of the article at right angles to the line of folding of said projecting edges, and means for folding the projecting edges of the wrapper at the other two sides of the article along the line of said creases.

42. In a wrapping machine, means for 115 folding a wrapper about one side of an article so that the edges of said wrapper project from three other sides of said article, means for folding the projecting edges of the wrapper backwardly against the article at the side of the article opposite that about which said wrapper was folded, means for creasing the backwardly folded edges of the wrapper adjacent the remaining two sides of the article, and means for folding the projecting edges of the wrapper backwardly against the article along the creased lines thereof.

43. In a wrapping machine, a receiving 125 platform having a guideway for articles deposited thereon, mechanism for feeding wrappers across said guideway, a member movable to push the articles to intercept and fold the wrappers around the articles in the 130

guideway, a revolving turret having pockets therein, a finger movable to push the articles into said pockets, a crimper movable toward said finger while the articles to be wrapped are held in a pocket in said turret by said finger, and means for sealing the wrappers.

44. In a wrapping machine, a receiving platform having a guideway for articles deposited thereon, mechanism for feeding wrappers across said guideway, a member movable to push the articles to intercept and fold the wrappers around the articles in the guideway, a revolving turret having pockets therein, an arm having a spring held finger thereon for pushing the articles into said pockets, a pivoted crimper arm having a crimper on the end thereof, means on said first named arm for abutting said crimper arm to rotate said crimper arm and move said crimper toward said finger while the articles to be wrapped are held in a pocket in said turret by said finger, and means for sealing said wrappers.

45. In a wrapping machine, a receiving platform having a guideway for articles deposited thereon, mechanism for feeding wrappers across said guideway, a member movable to push the articles to intercept and fold the wrappers around the articles in the guideway, a revolving turret having pockets therein, an arm having a pair of spring held fingers thereon for pushing the articles into said pockets, a pivoted crimper arm having a crimper on the end thereof, resilient means tending to rotate said crimper arm to move said crimper away from said finger, means on said first named arm for abutting said crimper arm to rotate said crimper arm against said resilient means and move said crimper toward said finger while the articles to be wrapped are held in a pocket in said turret by said fingers, and means for sealing said wrapper.

46. In a wrapping machine, a slotted receiving platform having a guideway for articles deposited thereon, mechanism for feeding wrappers across said guideway, a member movable to push an article to intercept and fold a wrapper around said article in said guideway, a revolving turret having a pocket therein, a finger extending through the slot in said guideway to engage and push said article into said pocket, a crimper movable toward said finger while the article to be wrapped is held in said pocket in said turret by said finger, and means for sealing said wrapper.

47. In a wrapping machine, a slotted receiving platform having a guideway for articles deposited thereon, mechanism for feeding wrappers across said guideway, a member movable to push the articles to intercept and fold the wrappers around the articles in the guideway, a revolving turret having pockets therein, a movable arm, a pair of

spring held fingers on said arm extending through the slot in said guideway to engage and push the articles into said pockets, a pivoted crimper arm having a crimper on the end thereof, means on said first named arm for abutting said crimper arm to rotate said crimper arm and move said crimper toward said fingers while the articles to be wrapped are held in a pocket in said turret by said fingers, and means for sealing said wrappers.

48. Means for wrapping a heat-sealing wrapper about an article with the inner faces of projecting margins in contact with each other, means for holding said projecting margins away from the wrapped article, and means for applying heat to the outer surfaces of both of said margins while so held to seal said margins together.

49. In a wrapping machine, the combination with means for heating and pressing together projecting portions of a wrapper disposed about an article with their inner surfaces in engagement with each other to thereby seal said projecting portions together, and means for applying a cooling medium to the outer surfaces of both of said projecting portions to thereby prevent the unsealing thereof.

50. In a wrapping machine means for folding a wrapper about an article with portions of said wrapper projecting beyond the article, means for heat sealing the projecting portions together, means for thereafter creasing a section of said projecting portions adjacent the article, and means for folding one of said sections along the creased line formed by said creasing means and against said article.

In testimony whereof I have signed my name to this specification on this 26th day of October, A. D. 1926.

MICHAEL J. MILMOE.
